UNITED STATES PATENT OFFICE.

LESLIE N. CRICHTON, OF EDGEWOOD PARK, PENNSYLVANIA, ASSIGNEE TO WESTINGHOUSE ELECTRIC AND MANUFACTURING COMPANY, A CORPORATION OF PENNSYLVANIA.

DISCONNECTING SWITCH.

Application filed November 2, 1920. Serial No. 421,250.

To all whom it may concern:

Be it known that I, LESLIE N. CRICHTON, a citizen of the United States, and a resident of Edgewood Park, in the county of Allegheny and State of Pennsylvania, have invented a new and useful Improvement in Disconnecting Switches, of which the following is a specification.

My invention relates to electric switches and particularly to switches of the knife-blade type.

The object of my invention is to provide a device of the above indicated character that may be readily opened regardless of adverse influences tending to hold it closed, such as the freezing together of its co-operating blade and jaw members.

Knife-blade switches, and particularly those employed in high-potential service as disconnectors, are subjected to freezing and corrosion of the contact members which render them difficult to open. Further, when the blade member of a knife-blade switch is of relatively great length and is disposed in certain positions, it is sometimes advisable or impossible to apply opening forces at the free end of the blade member where satisfactory leverage may be obtained. The opening of such a switch, at or beyond its pivot end, usually renders it necessary to apply a much greater force than is required at its free end.

In practicing my invention, I provide actuating means whereby a normal applied force at or near the pivot end of a frozen, or a relatively-long, switch arm is initially converted into a relatively great loosening or starting force for the blade member, separating any frozen or corroded portions, and, thereafter, permitting the ready opening of the switch in a usual manner.

Figure 1 of the accompanying drawings is a partial plan view of a high-potential, knife-blade, disconnecting switch embodying my invention, and

Fig. 2 is a partial side elevational view thereof.

My device comprises, in general, a base or supporting member 1, that is usually disposed on a tower or pole, at some distance from the ground, spaced insulators 2 and 3 secured to the base member 1, metal cap members 4 and 5 cemented, or otherwise secured, to the insulators 2 and 3, respectively, a terminal jaw member 6 and a pair of

similar jaw members 7 mounted on the cap members 4 and 5, respectively, a knife-blade structure 8 pivoted to the cap member 5 and adapted to bridge the jaw members 6 and 7, a lever mechanism 9 that is connected between the blade member 8 and an operating handle 10 through a rod 11.

The blade structure 8, being adapted for a switch of relatively great length, is preferably, constructed of complementary side-by-side blade members 12 that are joined at their free ends 13 to co-operate, as in a usual knife-blade switch, with the jaw member 6. The blade members 12 diverge toward their other end portions 14 that extend for some distance beyond the jaw members 7. Bearing members 15, mounted on the end portions 14, support a transverse pin 16 that extends through arms 17 of a lever structure 18 which is pivoted, by a pin or shaft 19, in bearing lugs 20 on the cap member 5. Portions 21 of the lever structure 18 extend outwardly and upwardly from the pin 19 and support a pin 22 at their upper ends by which the lever structure 18 is pivotally connected to the upper end of the rod 11. The rod 11, comprising a series of superposed insulators 23 and a straight portion 24, is pivoted, by a pin 25, to the handle lever 10 that is pivoted, by a pin 26, to a bracket member 27 that is secured to the base portion (not shown) of a pole or tower. A spring 28 is connected between pins 29 and 30 disposed, respectively, on the blade member 8 between the jaw members 6 and 7 and on a portion of the lever member 18 above the pin 16. Leaf springs 31, nested between the bearing members 15 and the blade members 12, have end portions 32 that extend to positions between the pin 19 and the portions 14 to prevent violent engagement between the pin 19 and the portions 14 during the operation of the switch.

In operation, when the handle 10 is actuated to move the rod 11 downwardly, the lever member 18 will be moved in clockwise direction about the pin 19. This motion will be transmitted through the pin 16 to the pivot end of the blade member 8 which will be lifted out of the jaw members 7 and moved in the general direction of its longitudinal axis to release the free ends 13 thereof from the jaw member 6. The leverages are such as to permit a nor-

- inal operating force on the handle 10 to effect a relatively great separating or loosening force on the blade member, thus ensuring its opening movement regardless of freezing and rendering the blade member free for comparatively easy further movement in disconnecting the circuit. The spring 28 serves to effect a quick-break, following action by the blade member 8.
- 10 While I have shown and described a particular form of my invention, changes may be effected therein without departing from the spirit and scope thereof, as set forth in the accompanying claims.
- 15 I claim as my invention:—
1. A knife-blade switch comprising a pair of spaced jaw members, a blade member extending therebetween and having an end portion extending beyond one of the jaw members, and means comprising a lever having a stationary pivot and direct pivotal connection to the blade member adjacent to said end portion, and an operating handle connected to the lever for disengaging said blade member from said one jaw member prior to its disengagement from the other jaw member.
2. A knife-blade switch comprising a pair of spaced jaw members, a blade member extending therebetween and having an end portion extending beyond one of the jaw members, a lever having a stationary pivot and direct pivotal connection to the blade member adjacent to said end portion, and cushioning means between the blade member and the lever.

3. A knife-blade switch comprising a pair of spaced jaw members, a blade member extending therebetween and having an end portion extending beyond one of the jaw members, a lever having a stationary pivot and a pivotal connection to the blade member adjacent to said end portion, cushioning means between the blade member and the lever, and a spring connecting the blade member and the lever.

4. A knife-blade switch comprising a pair of spaced jaw members, a blade member extending therebetween and having an end portion extending beyond one of the jaw members, a lever having a stationary pivot and a pivotal connection to the blade member adjacent to said end portion, cushioning means between the blade member and the lever, and an operating handle connected to the lever.

5. A knife-blade switch comprising a pair of spaced jaw members, a blade member extending therebetween and having an end portion extending beyond one of the jaw members, a lever having a stationary pivot and a pivotal connection to the blade member adjacent to said end portion, cushioning means between the blade member and the lever, a spring connecting the blade member and the lever, and an operating handle connected to the lever.

In testimony whereof, I have hereunto subscribed my name this 27th day of October 1920.

LESLIE N. CRICHTON.
